UNITED STATES PATENT OFFICE.

FRANK R. HAHN, OF DECATUR, ILLINOIS.

BUILDING CONSTRUCTION.

Application filed March 18, 1919, Serial No. 282,460. Renewed August 26, 1925.

To all whom it may concern:

Be it known that I, FRANK R. HAHN, a citizen of the United States, residing at Decatur, in the county of Macon and State of Illinois, have invented certain new and useful Improvements in Building Construction, of which the following is a specification.

This invention relates to double wall structures and the principal object is the provision of a double wall construction composed of a plurality of pre-cast slabs or units having means for securely fastening or connecting the opposed units together and also having means for spacing the units apart, and providing supporting posts, studs or columns, which may be left hollow or filled with cement, at various intervals thruout the length of the wall structure.

Another object of this invention is the provision in a wall of this character of slabs or units having laterally extending flange members which are arranged to cooperate with the corresponding flange members on the opposed slabs or units or with interposed filler blocks or slabs, whereby the opposed slabs or units may be positioned a greater or less distance apart.

Other objects of this invention include improvements in details of construction and arrangement whereby a strong and simple double wall construction is provided which may be quickly erected and which is strongly bonded and held together.

This application is filed as a continuing and divisional application in part, of my prior application as filed, Serial No. 151,903, filed March 2, 1917, concrete building construction, and Serial No. 236,080, filed May 23, 1918, building construction.

To the accomplishment of the foregoing and such other objects as may hereinafter appear, my invention consists in the construction, combination and arrangement of parts hereinafter described and then sought to be defined in the accompanying drawings forming a part hereof and which show merely for the purpose of illustrative disclosure a preferred embodiment of my invention, as well as two modifications thereof, it being expressly understood, however, that various other changes may be made in

practice within the scope of the claims without digressing from my inventive idea.

In the drawings—

Fig. 1 represents a top plan view of a portion of a wall constructed to embody the preferred form of my invention, this view being taken substantially on line 1—1 of Fig. 2.

Fig. 2 is a vertical cross section thru a wall constructed according to my invention taken substantially on line 2—2 of Fig. 1, and illustrating the use of filler blocks of different sizes.

Fig. 3 is a top plan view of a portion of a wall of a construction differing slightly from that shown in Fig. 1.

Fig. 4 is a perspective view of a portion of the wall utilizing slabs or units of a somewhat different construction from that illustrated in Figs. 1 and 3.

Fig. 5 is a top plan view of a part of a wall embodying various features of construction comprehended within my invention.

Fig. 6 is a perspective view of an intermediate bracing and spacing member.

Fig. 7 is a perspective view of another form of filler block having a supporting shoulder for supporting the unit on which the joist rests.

Fig. 8 shows a modification in the interlocking construction of the unit whereby while the same may interfit or interlock with each other, provision is also made for the reception of the bonding rod or hook at the junction of the two adjacent units.

Fig. 9 shows a top plan view of a part of a double wall construction without the filler block and utilizing a water proof composition between them to prevent dampness or moisture from penetrating.

Referring first to Figs. 1 and 2 of the drawings, the numeral 10 designates one of the slabs or units which may be of any size and shape and which are preferably provided with a groove 11 on one edge and the corresponding tongue 12 on the other edge, so that adjacent slabs or units will interfit. These slabs or units may also be provided with interfitting or interlocking end parts 13, (see particularly Fig. 4) for additional security.

In casting these slabs or units I may also provide laterally extending flange members 14 and 15, which are adapted to be positioned opposite each other when the wall 5 is constructed, the flange member 14 having the groove 16 in the end thereof and the flange member 15 having the corresponding tongue 17 in the end thereof whereby the opposed flange members may have an interfitting relation. With this arrangement the two parts of the double wall are comparatively close together. If it is desired to separate these two parts of the wall a greater distance, I utilize the filling 10 slabs or units 18 which have the corresponding tongue 19 and groove 20 on their ends so that they may interfit with the corresponding grooves and tongues on the ends of the flange members 14 and 15, as shown particularly in Fig. 1. Of course, it is to be understood that these blocks or slabs may be of any width so that the two parts of the double wall may be positioned at various distances apart, as illustrated in 15 Fig. 2, where the lower part of the wall is constructed so that the two parts thereof are separated a greater distance than the two parts in the upper part of the wall, the essential features of the construction being exactly the same and the dimensions 20 only, of the parts, being varied.

It is to be noted that the use of these flange members 14 and 15 with or without the filler blocks 18 provide a vertically 25 extending hollow column, stud or post. In order to secure the parts together properly, I utilize the hook members or rods 21 which are designed to connect the opposed slabs, the opposed pairs of flanges 14 and 15 or the opposed filler blocks 18. These hook members engage the exposed parts 22 of the reinforcing rods or wires which extend longitudinally near the edge parts of the various units, this exposure being made by 30 providing the recesses or sockets 23 of sufficient size to expose suitable lengths of the rods or wires 22 and to receive the hooked ends of the members 21. This forms a simple, convenient and effective method of 35 securely binding and connecting the opposed parts together. This connection may be rendered more secure and permanent by filling the hollow column or post with cement or other suitable plastic material. This is done or not, depending upon the character of the building, that is, whether 40 it is desired to be a temporary construction or a permanent construction.

The construction shown in Fig. 3 is the same in all essential details with that shown in Figs. 1 and 2, except that the laterally extending flange members 14 and 15 are omitted. The filler slabs or units 24 are positioned at various intervals throughout the 45 length of the wall and these filler slabs

or units, as well as the opposed parts of the main slabs or units are connected by the hook members 21, the construction being exactly the same as that shown in Fig. 1. This is merely a somewhat simpler form 70 of construction.

In Fig. 4, I show another slightly modified form in which the slabs or units 10 are provided with the laterally extending flange members 25 which are arranged to have interlocking and interfitting end parts 26 similar to the interlocking and interfitting ends 13 of the slabs or units 10. The exposed reinforcing members may be similarly connected by the hook members 21 80 as previously described.

In Fig. 5 of the drawing I illustrate the various features of construction hereinbefore described and also certain other details of construction which are within the purview of my invention and cooperate to provide means for taking care of peculiar conditions arising from the erection of such structures.

Referring first to Fig. 6, the numeral 27 shows an intermediate facing and bracing unit. This unit may be used at an intermediate place in the wall and also at the joint of the adjacent slab. It is provided with the cut out portion 28 on each edge terminating in the feather edges 29 which are the bearing edges engaging the inner surfaces of the opposed members of the double wall construction which reduces to a minimum the possibility of conveying dampness thru the wall. The upper portion of this unit is provided with the longitudinally extending groove or recess 30 which is adapted to receive the securing rod or hook 21 previously described. The ends of this hook are secured over the exposed portion of the reinforcing wire, as previously described and as clearly illustrated in Fig. 5. This particular description applies to the use of this unit as an intermediate supporting and bracing element.

Where it is used at the joint between adjacent slabs a slight modification is preferably made in the construction of the slabs or units, this being particularly illustrated in Fig. 8 and also at the bottom of Fig. 5. In these slabs or units the interfitting tongues and grooves are provided on the ends, as indicated at 31 and 32, but the tongue 31 does not extend the full width or height of the unit, terminating a short distance from the top edge thereof, the remainder of the edge being formed with the groove 33 which matches with the oppositely disposed groove 32. It is in these openings that the hook members 21 are positioned, it being, of course, understood that they rest in the recess 30 formed in the top of the unit 27. This recess, as

well as the openings in the edge parts of the slabs or units may be filled with cement or other suitable plastic material, so as to permanently secure the hook members in position.

5 In order to provide an intermediate supporting means for the units which support the joists of the building I utilize a particular form of filler block 34, see Fig. 7, which is of the general conformation of the previously described filler block or unit 18, having however, in addition thereto, the overhanging flange or shoulder 35 on which these supporting units may rest.

10 At the inside corner construction, where the two inner members of the double wall intersect, I provide the slabs or units 36 and 37. These slabs or units have the oppositely disposed cut out portions or recesses 20 38 and 39 whereby these slabs may interfit and intersect, as shown in Fig. 5.

15 In the event that the double wall construction is utilized without the spacing or filler blocks 18, it may become necessary to interpose a suitable waterproof composition between the two members of the wall. This is illustrated in Fig. 9, the numeral 40 designating this composition.

20 It is to be noted in connection with Figs. 30 5 to 9 inclusive that I provide the vertically extending tongue and groove interfitting connection, and in Figs. 1 to 4 inclusive I provide in addition the horizontally or longitudinally extending groove interfitting connection between the various slabs or units. It is to be understood that these may be used together or interchangeably according to the desire and working conditions.

40 It is to be noted also that in these wall constructions the interfitting and interlocking end parts break joints so as to render the construction stronger, as is well understood.

45 Having described my invention, what I claim is:—

1. A construction of the character described, including in combination, a plurality of slabs or units arranged to form a double wall construction, certain of said slabs or units in each part of said double wall having laterally extending flanges adapted to interfit with the opposed flanges whereby hollow columns or posts are provided at intervals thruout the length of the wall, and filler blocks interposed between said laterally extending flange members whereby hollow columns or posts are provided thruout the length of the wall, and securing means extending across said hollow columns or posts for holding said parts together.

2. A construction of the character described including in combination a plurality of slabs or units adapted to be arranged

to form a double wall construction, certain of said slabs or units in each part having laterally extending flange members, certain of the flange members being provided with a tongue on the end and others being provided with a groove on the end whereby said opposed flange members may interfit, and filler blocks or members, each of which has a tongue on one end and a groove on the other end adapted to fit with the corresponding tongues and grooves on the ends of the laterally extending flange members whereby hollow columns or posts may be provided at intervals thruout the length of the wall construction, and securing means extending across the hollow columns or posts for holding the parts together.

3. A construction of the character described including in combination a plurality of slabs or units arranged to provide a double wall construction, each of said slabs or units having longitudinally extending reinforcing rods positioned near the edge thereof, means interposed between the two parts of said wall for spacing the same apart, certain of said units being formed with recesses to expose parts of said reinforcing rods and hook members adapted to connect the exposed parts of said reinforcing rods in the opposed members.

4. A construction of the character described, including in combination a plurality of longitudinal units adapted to be arranged to form a double wall construction, a plurality of filler units adapted to be interposed at intervals thruout the length of said double wall, each unit having a longitudinal reinforcement near one edge and provided with cutout portions to provide recesses exposing short lengths of said reinforcements, engaging members adapted to engage the exposed lengths of said reinforcements of the opposed units, said filler units providing hollow columns or posts which may be filled with a suitable plastic material to form a supporting column.

5. A construction of the character described, including in combination, a plurality of slabs or units arranged to form a double wall construction, certain of said slabs or units in each part of said double wall having laterally extending flanges adapted to interfit with the opposed flanges whereby hollow columns or posts are provided at intervals thruout the length of the wall, and filler blocks interposed between said laterally extending flange members whereby hollow columns or posts are provided thruout the length of the wall, and securing means extending across said hollow columns or posts for holding said parts together, said filler block having an enlarged shoulder at the upper end thereof to form an intermediate supporting means in said wall construction.

6. A building construction of the char-

acter specified, including in combination a plurality of slabs or units arranged in spaced relation to provide a double wall, and means interposed between said two parts to space them apart and to form a hollow column or post between the two parts and means extending across said hollow column or post to connect said parts together and intermediate spacing members positioned between the two parts of said double wall construction and securing means in connection with said intermediate means connecting the two parts of the double wall construction at the place where said intermediate means is inserted.

7. A construction of the character described, including in combination, a plurality of slabs or units arranged to provide a double wall construction, filler blocks interposed between said two series of slabs or units at intervals throughout the length of the wall to provide a plurality of hollow columns or posts within the double wall, and securing means extending across the hollow columns or posts for connecting the parts together, and intermediate means interposed at intervals throughout the double wall construction for spacing and bracing the two parts of the double wall, said intermediate means each comprising a unit having its top and bottom edges which engage the two parts of the wall feathered and having a longitudinal recess in its top surface and securing means connected to the two parts of said double wall construction and positioned in said recess in said intermediate means.

8. A construction of the character described, including in combination, a plurality of slabs or units arranged in two series to provide a double wall construction, each of said slabs or units having a tongue and groove construction at one end whereby adjacent units may interfit, certain of said tongue constructions being cut away a short distance and the end of this unit being provided with a recess adapted to register with the corresponding recess or groove in the ad-

jacent slab or unit to provide an opening and securing means extending between the two parts of the double wall construction and having hooked ends positioned in said opening.

9. A construction of the character described, including in combination, a plurality of slabs or units arranged in two series to provide a double wall construction, each of said slabs or units having a tongue and groove construction at one end whereby adjacent units may interfit, certain of said tongue constructions being cut away a short distance and the end of this unit being provided with a recess adapted to register with the corresponding recess or groove in the adjacent slab or unit to provide an opening and securing means extending between the two parts of the double wall construction and having hooked ends positioned in said opening and intermediate spacing and bracing means interposed between the said joints of the opposed members of the two parts of the double wall construction.

10. A building unit having a laterally extending flange portion and also having a reinforcement extending longitudinally therein and positioned near one edge, said unit being formed with a recess in one edge to expose part of said reinforcement to provide an engagement member to receive engaging means.

11. A building unit having a laterally extending flange portion and also having a reinforcement extending longitudinally therein and positioned near one edge, said unit being formed with a recess in one edge to expose part of said reinforcement to provide an engagement member to receive engaging means, said laterally extending flange portion being constructed so as to provide means with which the corresponding flange portion on the opposed unit may fit.

In testimony whereof I hereunto subscribe my name.

FRANK R. HAHN.
